(57) **CLAIM**

The ornamental design for combat boot, as shown and described.

DESCRIPTION

FIG. 1 is a perspective view of combat boot showing my new design.

FIG. 2 is a right side view thereof;

FIG. 3 is a left side view thereof;

FIG. 4 is a front view thereof;

FIG. 5 is a top view thereof;

FIG. 6 is a bottom view thereof; and,

FIG. 7 is a rear view thereof.

The broken line shown in the drawings is included for the purpose of illustrating portions of the combat boot and forms no part of the claimed design.
